UNITED STATES PATENT OFFICE.

GEORGE MARGOLIN, OF NEW YORK, N. Y., ASSIGNOR TO A. R. MOSLER & COMPANY,
OF MOUNT VERNON, NEW YORK.

SPARK-PLUG.

1,397,321.

Specification of Letters Patent.

Patented Nov. 15, 1921.

Application filed January 31, 1920. Serial No. 355,482.

To all whom it may concern:

Be it known that I, GEORGE MARGOLIN, a citizen of the United States, and resident of the borough of Manhattan, in the city and State of New York, have invented a new and useful Improvement in Spark-Plugs, of which the following is a specification.

With the present low grade of fuel for hydrocarbon engines, it has been very difficult, if not impossible, to keep the spark plugs from fouling and short circuiting, due to the accumulation of carbon and oil in the spark plug, and especially oil on the inner exposed portion of the mica insulation surrounding the center electrode. It has also been very difficult, owing to excessive heat conditions to keep the said mica insulation from breaking up or disintegrating, especially when the spark plugs are used in engines of high compression. The object of my invention is to provide means for protecting as far as possible, the inner exposed portion of the mica insulation from direct contact with the combusted gases and the materials which would tend to soot up the insulation.

The means which I have found suitable for accomplishing the above results is a baffle plate of peculiar form located at the required point in the spark plug chamber, the said baffle plate surrounding and spaced from the reduced inner end of the center electrode and dividing the spark plug chamber into inner and outer compartments connected by a restricted passage.

A practical embodiment of my invention is represented in the accompanying drawings, in which—

Figure 1 represents partly in side elevation and partly in longitudinal central section a spark plug embodying my invention.

Fig. 2 is an inner end view of the spark plug.

The sleeve 1 is shown as screwed into the outer end of the shell 2. The center electrode comprises an enlarged body portion 3 tapered toward the outer end of the plug and a reduced spindle portion 4 projecting from the inner end of the body portion 3.

The spark plug chamber in the shell 2 is divided by a baffle plate 5 into inner and outer compartments 6 and 7, connected by a restricted passage 8 through which the re-

duced spindle portion 4 of the center electrode extends.

The other electrode 9 is carried by the shell 2 and terminates in a knife edge disposed longitudinally to the reduced portion 4 of the center electrode, said shell electrode coacting with the center electrode to form 60 sparking points in the outer compartment 7 of the spark plug chamber.

The enlarged body portion 3 of the center electrode is provided with a mica wrapping 10 which extends from end to end of the body portion of the center electrode and snugly seats the electrode in the sleeve 1. Transverse layers of mica insulation 11 surround the mica wrapping 10 between the outer end of the sleeve 1 and the washer 12. 70

The baffle plate 5 is directed toward the inner end of the plug into the outer compartment 7.

The walls of the restricted passage 8 through the baffle plate are made slightly 75 flaring toward the inner end of the plug and the smaller diameter of this passage 8 is less than the diameter of the body portion 3 of the center electrode at its inner end, so that the combusted gases which might pass 80 through the restricted passage will be directed against the inner end of the body portion 3 of the center electrode and against the reduced portion 4 thereof, thereby protecting the mica wrapping 10 from direct contact with the said combusted gases. 85

The baffle plate 5 is made thinner as shown at 13 between the shell 2 and the restricted passage 8, so that the rapid radiation of heat from the baffle plate to the shell 90 is prevented, thus keeping the mica insulation within the inner compartment 6 of the spark plug chamber hot enough without subjecting it to the deleterious effects of direct contact with the hot combusted gases 95 and oil.

This baffle plate is formed of such thickness that it will become hot enough to burn up any carbon deposited thereon and to vaporize or burn off any oil or fuel which 100 may be splashed thereon. This baffle plate will also vaporize oil or fuel which may be deposited thereon, during idling or slow running of the engine.

It is evident that various changes may be 105 resorted to in the construction, form and

arrangement of the several parts without departing from the spirit and scope of my invention; hence I do not intend to limit myself to the particular embodiment herein shown and described, but

5 What I claim is:

1. In a mica spark plug, a shell, a baffle plate dividing the spark plug chamber into inner and outer compartments connected by 10 a restricted passage, and a center electrode having a mica covering projecting into the inner compartment, said baffle plate being constructed to prevent a too rapid radiation of the heat from the baffle plate to the shell, 15 for keeping the exposed portion of the mica covering sufficiently hot without submitting it to the deleterious effects of direct contact with the hot combusted gases and oil.
2. In a mica spark plug, a shell, a baffle plate formed integral with the shell and dividing the spark plug chamber into inner and outer compartments connected by a restricted passage, and a center electrode having a mica covering projecting into the 25 inner compartment, said baffle plate being constructed to prevent a too rapid radiation of the heat from the baffle plate to the shell, for keeping the exposed portion of the mica covering sufficiently hot without submitting it to the deleterious effects of direct contact 30 with the hot combusted gases and oil.

3. In a mica spark plug, a shell, a baffle plate dividing the spark plug chamber into inner and outer compartments connected by 35 a restricted passage, and a center electrode having a mica covering projecting into the inner compartment, said baffle plate having a thinner portion to prevent a too rapid radiation of heat from the baffle plate to the shell, for keeping the exposed portion of the 40 mica insulation sufficiently hot without submitting it to the deleterious effects of direct contact with the hot combusted gases and oil.

4. In a mica spark plug, a shell, a baffle plate formed integral with the shell and dividing the spark plug chamber into inner and outer compartments connected by a restricted passage, and a center electrode having 45 a mica covering projecting into the inner compartment, said baffle plate having a thinner portion to prevent a too rapid radiation of heat from the baffle plate to the shell, for keeping the exposed portion of the mica insulation sufficiently hot without submitting it to the deleterious effects of direct contact 50 with the hot combusted gases and oil.

In testimony, that I claim the foregoing as my invention, I have signed my name this 55 twenty-fourth day of January, 1920.

GEORGE MARGOLIN.
